UNITED STATES PATENT OFFICE.

JOHN WOOL GRISWOLD, OF TROY, NEW YORK.

BARBED-WIRE FENCE.

SPECIFICATION forming part of Letters Patent No. 465,645, dated December 22, 1891.

Application filed June 15, 1891. Serial No. 396,262. (No model.)

To all whom it may concern:

Be it known that I, JOHN WOOL GRISWOLD, of Troy, Rensselaer county, New York, have invented a new and useful Improvement in 5 Barbed-Wire Fences, of which the following is a specification.

My invention relates to that class of wire fencing which is composed of a series of links, usually barbed; and it consists in the construction of said links and their combination to form a continuous fencing.

In the accompanying drawings, Figure 1 is a plan view of my improved fencing. Fig. 2 is a side view. Fig. 3 is a sectional view on 15 the line 3 3 of Fig. 1.

Similar letters of reference indicate like parts.

Each link *a b* consists of a length of wire *A*, doubled or halved on itself to form at one 20 end of said link the eye *B*. One end of the doubled-over wire *A* is bent to form an eye *C*. The other end of the doubled-over wire *A* is bent in the opposite direction to form an eye *D*. The two eyes *C* and *D* are placed 25 side by side, as shown. One extremity *E* of the wire *A*, after the eye *C* is formed, passes outside of its own standing part and transversely across both parallel strands of the link on one side thereof. The other extremity 30 *F* of the wire *A*, after the eye *B* is formed, passes outside of its own standing part and then transversely across both parallel strands of the link on the side opposite to the end *E*.

The extremities *E* and *F* thus lie on opposite sides of the link and protrude to form barbs. 35 In uniting these links together the eye *B* of one link engages with the eyes *C D* of the adjacent link. The eyes *C* and *D* are placed parallel one to the other.

I claim—

1. A wire-fencing link composed of a length of wire doubled to form a loop or eye *B* at one extremity of the link and having its extremities bent in relatively opposite directions to produce the eyes *C D*, each extremity *E F* of said wire passing outside of its own standing part and then transversely across both parallel strands of the link on opposite sides thereof and protruding to form a barb. 40
2. A wire fencing composed of a series of 50 enchain'd links, each link being composed of a length of wire doubled to form a loop or eye *B* at one extremity of the link and having its extremities bent in relatively opposite directions to produce the eyes *C D*, each extremity *E F* of said wire passing outside of its own standing part and then transversely across both parallel strands of the link on opposite sides thereof and protruding to form a barb, the eye *B* of one link engaging with 55 the eyes *C D* of the next adjacent link. 60

JOHN WOOL GRISWOLD.
